UNITED STATES PATENT OFFICE.

THOMAS S. HALL, OF STAMFORD, ASSIGNOR TO HALL'S ELECTRIC RAILWAY SWITCH AND DRAWBRIDGE SIGNAL COMPANY, OF NEW HAVEN, CONNECTICUT.

IMPROVEMENT IN SWITCH-ALARM CONNECTIONS.

Specification forming part of Letters Patent No. 90,744, dated June 1, 1869.

To all whom it may concern:

Be it known that I, THOMAS S. HALL, of Stamford, Fairfield county, Connecticut, have invented a new and Improved Connection for Switch Alarm and Signal; and I do hereby declare that the following is a full, clear, and exact description thereof, which will enable others skilled in the art to make and use the same, reference being had to the accompanying drawings, forming part of this specification.

Figure 1 represents a vertical longitudinal section of my improved signal-connection. Fig. 2 is a vertical transverse section of the same.

Similar letters of reference indicate corresponding parts.

This invention relates to certain improvements on the electric railway-switch for which Letters Patent No. 62,414 were granted to me on the 26th day of February, 1867.

The present invention relates more particularly to a new mechanism and action of the switch-connection, and in a new manner of protecting the connecting-lever.

The connecting apparatus was in the aforesaid Letters Patent represented as arranged below ground, and was therefore difficult of access and subject to injury by water or otherwise. In the present case the whole apparatus is above ground, and protected in a box or case, so as to be ready of access and easy to repair.

A in the drawing represents a metal or other box or case, containing on a sliding side plate, B, two (or more or less) cylinders, C. Within the upper part of each cylinder C is securely arranged an insulated block, D, through which two metal plates, E E', connected with the wires F F' of the battery, are fitted.

Into the lower part of each cylinder is fitted

a loose plug, G, carrying a metallic projecting plate, a, which fits between the plates E E' without touching the same. The plug G connects with and is fitted on a lever, H, which is slotted. I is the lever connecting with the switch. This lever enters the box A at one end and has projecting pins b b, that fit through the slots of the levers H, respectively. When the switch is displaced the lever I is longitudinally moved, so that the pins b will cause the levers H to swing. Thereby the plugs G are turned to swing the lug a, which is then brought in contact with the plates E E' to establish metallic connection between the wires F F'. Thus, whenever the switch is displaced the wires are at once connected to establish an electric current by which the signal is operated. When the hinged or movable cover J of the box A is opened the whole inner apparatus can be withdrawn, as it is attached to the movable plate B.

I claim as new and desire to secure by Letters Patent—

1. Conducting the lever I from the switch into a movable box in which the device for establishing an electric current is contained, substantially as herein shown and described.

2. Attaching the cylinders C that contain the wire-connecting devices and their appendages to a movable sliding plate, B, which is arranged in a box, C, substantially as herein shown and described.

3. The combination of the cylinder C with the insulated block D, metal plates E E', oscillating plug G, lug a, levers H and I, all arranged and operating substantially as herein shown and described.

THOMAS S. HALL.
